UNITED STATES PATENT OFFICE.

FREDERICK BOGENBERGER, OF MILWAUKEE, WISCONSIN.

GRAVITY SASH-LOCK.

934,655.

Specification of Letters Patent. Patented Sept. 21, 1909.

Application filed November 23, 1908. Serial No. 464,858.

To all whom it may concern:

Be it known that I, FREDERICK BOGENBERGER, a citizen of the United States, residing at Milwaukee, in the county of Milwaukee and State of Wisconsin, have invented 5 certain new and useful Improvements in Gravity Sash-Locks of which the following is a specification.

My invention relates particularly to a class 10 of gravity actuated sash locks which are used in connection with fire proof windows, or windows of sheet metal construction, having sash which swing on pivots and which are designed to close automatically.

The object of my invention is to provide 15 a lock for this purpose, which is so constructed that its parts can be easily and cheaply manufactured, and quickly assembled.

My invention is further arranged to be fitted 20 and adjusted to each individual window with a minimum of labor and trouble.

My invention also aims to provide a lock 25 which is perfect and responsive in its action.

On August 24, 1908, I filed an application, 30 Serial No. 450,057, for Letters Patent on improvements in gravity sash locks. This invention or lock is to be used on the upper rail of the window sash. My present invention is to be used in connection with this first invention and is to be fastened on the lower rail of the sash.

With these and other objects in view, my invention consists of certain novel features of construction, combination and arrangement of parts as will be described and particularly pointed out in the appended claims.

In the accompanying drawings, Figure 1, represents a face view of my invention and portions of the frame and sash to which it is attached. Fig. 2, is a side view of my invention, showing a cross section of the sash bar and frame to which it is attached. Fig. 3, is a templet view of the support which carries the pawl or locking member. Fig. 4, is a vertical section of a window frame and sash with my present invention attached, and illustrating its operation.

In the embodiment illustrated my invention comprises, a pawl 1, pivotally carried 50 by the supporting arch 2, which is fastened to the sash rail 3, and a strike plate 4, fastened to the sill or cross bar of the window frame, 5. The pawl 1, is a heavy compact body of a uniform breadth, having a head 55 or weighted portion 6, the under side of which is cut to form the hook 7. This head

6, unites with the body portion 8, through which is a hole, in which the pivot pin 9, is inserted. The supporting arch 2, of which Fig. 3, is a templet view is made of sheet 60 steel or other suitable metal, and bent so as to form two fastening flanges 10, two supporting flanges 11, and a connecting arch 12. Two stove bolts 13, fasten this supporting arch to a reinforcing plate of heavy metal 65 14, which is in turn fastened to the inside of the sash rail 3, which is of relatively light iron. The supporting flanges 11, have holes 15, provided through which the pivot pin 9, passes and over which said pin is riveted. 70 The strike plate 4, is of heavy metal bent so as to form a striking edge or stop 16, which engages the hook 7, and a flat fastening portion 17. This flat fastening portion is provided with two oblong slots, 18, through 75 which the two bolts 19, pass and fasten in screw engagement with the reinforcing plate 20, fastened to the inside of the sill 5. Another hole which is threaded is provided, and in which the set screw 21, is placed. 80

As has been mentioned already, it is intended that my invention be used in connection with a gravity sash lock placed on the upper rail of the sash. This arrangement provides that the sash shall close automatically in case of fire. In Fig. 4, we have a window frame, 22, having a sash 23, which swings on the pivots 24. My invention is fastened to the lower sash rail 3, and sill 5. 85

The operation of these locks is secured as 90 follows: On the upper side of the head 6, is an eyelet, 25, through which the chain 26, is fastened. From here the chain is passed up through the pulley 27, of the upper lock 28, and then down again. Now it will be seen 95 that when a pull is exerted on the chain at 29, both lower and upper locks will disengage from their respective strike plates, thus unlocking the sash and at the same time allowing it to open. Whenever the chain 26, 100 is loosened the sash will close automatically, and the locks will catch of their own accord. In case of fire the chain is separated at the fusible link 30.

The pawl 1, is limited in its movement so 105 that its action should be quick and positive. The upward movement is limited when the head 6, strikes the connecting arch 12, at its edge 31. The downward movement is limited when the tail 32, of the pawl 1, strikes the under side of the connecting arch 12.

Adjustment to overcome any irregularities

in the action of my invention is secured in the following way: The strike plate 4, has the oblong slots 18, through which the holding bolts 19, pass. Before these bolts are 5 tightened the strike plate 4, is moved up or down as desired, thus keeping the strike plate at the required height. Adjustment in and out is secured by tightening or loosening the set screw 21. This set screw is a 10 valuable part of my invention as it secures an object that has not been obtained hitherto.

From the foregoing description it will be seen that the action of my invention is positive and that it secures all the advantages 15 sought in the foregoing objects.

While the description has shown my lock used in connection with a window of hollow sheet metal construction, it is to be understood that it can be used on windows made 20 of wood or other materials should occasion arise.

Having thus described my invention, what I claim as new and desire to secure by Letters Patent is:

25 1. The combination with a window frame having a tilting or swinging sash, of a gravity sash lock, comprising a supporting

arch carried on the lower rail of said sash, a pawl pivotally carried by said arch, means to limit the movement of said pawl in said arch, said arch and pawl being adapted to swing outwardly with said sash, and an adjustable strike plate fastened to the sill of said window to engage the said pawl when the sash is closed. 35

2. In a gravity sash lock of the character described, the combination of a pivoted pawl, a supporting arch adapted to carry said pawl, a strike plate comprising a piece of heavy bent metal, one end adapted for engagement with said pawl, the other being a flat fastening body, said body portion being provided with two oblong slots, and a threaded aperture, holding bolts passing through said oblong slots, and a set screw 40 45 adapted to work in said threaded aperture.

Signed by me in Milwaukee, county of Milwaukee, and State of Wisconsin, this 22nd day of October, 1908.

FREDERICK BOGENBERGER.
